UNITED STATES PATENT OFFICE.

CHESTER W. CHEATHAM, OF SEATTLE, WASHINGTON, ASSIGNOR OF ONE-HALF TO
J. N. NISSEN, OF SEATTLE, WASHINGTON.

AUTOMATIC REGULATING GATE.

Application filed June 1, 1925. Serial No. 33,926.

This is an adjustable, automatically regulated gate for providing a constant flow of water through a channel, regardless of the fluctuating of the level of water.

5 The object of the invention is to provide a device for automatically regulating the flow of water in a channel or the like.

Another object of the invention is to provide an automatic regulating device for controlling the flow of water in a channel or the like which may readily be adjusted.

10 And the further object of the invention is to provide an adjustable automatic regulating gate which is of a simple and economical construction.

15 With these ends in view, the invention embodies a U shaped frame with a flat plate at the bottom, a series of openings in the side members and an inclined plate slidably supported between the side members.

20 Other features and advantages of the invention will appear from the following description, taken in connection with the drawings, wherein:—

25 Figure 1 is a cross section through the gate and channel or the like in which it may be placed.

Figure 2 is a front view of the gate.

30 Figure 3 is a view similar to that shown in Figure 1, showing the gate after it has been moved upward.

35 In the drawings I have shown my device as it would be constructed wherein numeral 1 indicates a U shaped frame, numeral 2, the adjustable inclined plate and numeral 3 a channel or the like in which the gate may be placed.

40 The frame 1 is constructed with two vertical bars as indicated by the numerals 4 and 5 and a horizontal bar as indicated by the numeral 6, the lower part of the frame is provided with a plate 7 and the upper part of the vertical members 4 and 5 are provided with holes 8 and 9 for adjustably holding the plate 2. The frame 1 is held at the edges by rollers 10 and 11 and one side and guide members 12 on the opposite side, both the rollers and guide members being attached to the sides of the channel 3. All 45 though this frame is disclosed and described as being of a rectangular shape it is understood that it may be of any suitable shape to fit a channel or the like of any suitable design.

55 The member 2 is provided with a plate 13

which may be straight or may have its forward end curved slightly downward and its rear end curved slightly upward as shown in Figure 1. The plate is provided with side members 14 having flanges 15 and 16 to engage the bars 4 and 5 as shown in Figures 1 and 2. It will also be observed that the flanges 15 may be provided with openings 17 so that the member 2 may be held in the openings 8 and 9 of the bars 4 and 5 by pins 18 as shown. It will also be observed that the elevation of the member 2 may readily be adjusted by removing the pins 18 and sliding the member 2 upward and downward.

50 It will be understood that changes may be made in the construction without departing from the spirit of the invention. One of which changes may be in the design or shape of any of the members, another may be in the design of the member 2, or in the means for slidably holding it to the bars 4 and 5 or in the means for adjustably holding it to the bar, and still another may be in the design, arrangement or shape of the channel in which the device may be placed.

55 The construction will be readily understood from the foregoing description. To use the device, the frame 1 may be inserted in a channel or the like as shown in the drawing and it will be observed that the member 2 may be set to any suitable position on the frame so that any amount of water desired may flow through the weir. It will be observed that as the surface of the water engages the under side of the inclined plate 13 it will raise the entire frame and the opening between this plate and the plate 7 will thereby be raised to keep the flow of the water constant regardless of the level of the water in the channel. By adjusting the position of the member 2, the opening through which the water flows may be regulated, so that the same amount of water will be permitted to flow through the weir or into the channel at all times, even though the water level may vary considerably.

60 Having thus fully described the invention, what I claim as new and desire to secure by Letters Patent, is:—

65 1. In a device of the class described, a 700 slideable frame, an adjustable opening in the said frame, a means for slidably supporting the said frame in a channel through which water may pass, and an inclined baffle 750 110

plate in the upper part of the said opening for raising and lowering the said frame as the water level varies.

2. In a gate for providing a constant flow of water through a channel, a slidable frame with an adjustable opening and an inclined baffle plate adjustably held on the said frame and forming the upper part of the said opening for raising and lowering the opening, said means being operated by the rise and fall of the water level.

3. In a device for keeping the flow of

water through a channel constant, a slidable frame having an opening therein, an inclined plate adjustably held in the said frame for forming the upper part of the said opening and a means for holding the said frame in a channel or the like.

4. In a device for keeping the flow of water through a channel constant, a slidable frame having an opening therein, and an inclined plate adjustably held in the said frame for forming the upper part of the said opening.

CHESTER W. CHEATHAM.
